US00D842302S

(12) **United States Design Patent** (10) Patent No.: **US D842,302 S**
Man (45) Date of Patent: **** Mar. 5, 2019**

(54) **PORTABLE RADIO FREQUENCY TAG
READER TRAY**

(71) Applicant: **Megabyte Limited**, Hong Kong (HK)

(72) Inventor: **Chun Sing Matthew Man**, Hong Kong (HK)

(73) Assignee: **Megabyte Limited**, Hong Kong (HK)

(**) Term: **15 Years**

(21) Appl. No.: **29/591,000**

(22) Filed: **Jan. 16, 2017**

(30) **Foreign Application Priority Data**

Jul. 14, 2016 (HK) 1601348
